Primary Examiner—James M. Gandy
Attorney, Agent, or Firm—Trexler, Bushnell & Wolters,
Ltd.

[73] Assignee: Ryder International Corporation, Arab, Ala.

[57] CLAIM

The ornamental design for a casing for contact lens sterilizer, substantially as shown and described.

DESCRIPTION

FIG. 1 is a top plan view showing our new design for a casing for contact lens sterilizer;

FIG. 2 is a side elevational view thereof, the opposite being a mirror image of that shown;

FIG. 3 is a front elevational view thereof;

FIG. 4 is a rear elevational view thereof.

The bottom of the casing is plain and unornamented.

[**] Term: 14 Years

[21] Appl. No.: 357,591

[22] Filed: Mar. 12, 1982
